(57) **CLAIM**

The ornamental design for a component of an air quality sensing device, as shown and described.

DESCRIPTION

FIG. 1 is a perspective view of a component of an air quality sensing device showing my new design.

FIG. 2 is a bottom rear perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side view thereof.

Features shown in broken line are for illustrative purpose only and form no part of the claimed design.
